E V

OF D 12,300

Design No. 12,300, dated June 7, 1881.

UNITED STATES PATENT OFFICE.

CHARLES PENCHARD, OF LONG ISLAND CITY, ASSIGNOR TO WILLIAM M. WATSON, JOHN M. KARSCH, AND WILLIAM E. WATSON, OF NEW YORK, N. Y.

DESIGN FOR A CHAIR.

SPECIFICATION forming part of Design No. 12,300, dated June 7, 1881.

Application filed April 26, 1881. Term of patent 3½ years.

To all whom it may concern:

Be it known that I, CHARLES PENCHARD, of Long Island City, in the county of Queens and State of New York, have invented a new and Improved Design for Chairs; and I do hereby declare that the following is a full, clear, and exact description thereof.

This invention relates more particularly to the chair-back or portion above the seat, and it may be applied to chairs of various descriptions without regard to the style of seat or legs.

In the accompanying photographic illustration, A represents the shield or main surface of the back.

B B are the back-posts, which are beaded longitudinally and vertically, said beads extending entirely over the tops of said posts.

C is the top rail of the chair-back, having its ends connected to the upper portions of the inner sides of the posts B B. The top edge of this rail C is arched and its lower or bottom edge is straight. The rail is divided about midway of its width by a horizontal line drawn parallel with the bottom edge. In the upper division, above said line, is an arch-shaped veneer, d, on which is carved an ornamental figure. In the lower division, below said line, is a row of quadrangular-based pyramidal bosses, e, arranged diagonally, with lozenge-shaped depressions f between them.

G is a horizontal bar, beaded longitudinally and having its ends connected to the back posts, B B, and forming the bottom rail of the shield.

H H are the side posts of the shield, having their lower ends connected to the bar G, and their upper ends connected to the top rail, C.

J is a horizontal bar, forming the top rail of

the shield and having its ends connected to the side posts, H H, of said shield.

Between the top rail, J, of the shield and the top rail, C, of the chair-back are a number of short spindles, K, having swells and beads turned on them.

45

I claim as my invention—

1. The design for a top rail of a chair-back herein described, consisting of a bar, C, having its top edge arched and its bottom edge straight, and provided with an arch-shaped ornamental-carved veneer, d, and a series of pyramidal bosses, e, with lozenge-shaped depressions f between them, substantially as set forth.

2. The design for a chair-back herein described, consisting of the posts B B, having beads running longitudinally and extending over the top ends, the top rail, C, having its top edge arched and its bottom edge straight, and provided with an ornamental arched veneer and a series of pyramidal bosses and lozenge-shaped depressions, and the bottom rail, G, beaded longitudinally, and having its ends connected to the posts B B, substantially as set forth.

55

3. The design for a shield herein described, consisting of the bottom rail, G, the side posts, H H, extending from said bottom rail, G, to the top rail, C, the top rail, J, having its ends connected to the side posts, H H, and the spindles K, having swells and beads turned on them, and extending from the top rail, J, to the top rail, C, substantially as set forth.
